UNITED STATES PATENT OFFICE.

EDGAR F. PALMER AND ORION G. HARDIN, OF LOUISVILLE, KENTUCKY.

DAVENETTE.

1,333,822.

Specification of Letters Patent. Patented Mar. 16, 1920.

Application filed September 30, 1915. Serial No. 53,211.

To all whom it may concern:

Be it known that we, EDGAR F. PALMER and ORION G. HARDIN, citizens of the United States, and residents of the city of Louisville, county of Jefferson, and State of Kentucky, have invented certain new and useful Improvements in Davenettes, of which the following is a specification.

This invention relates to "two fold davenettes" or sofa beds.

An object of the invention is to provide a davenette, (that is a short davenport) or sofa bed having two folding sections which open with a single forward motion.

15 A further object is to provide an article of furniture of the class described which shall be economical in construction, efficient in operation and durable in service.

With the foregoing and other objects in view, the invention consists of the novel construction and arrangement of parts illustrated in the accompanying drawing which forms a part of this specification, wherein is set forth an embodiment of the invention, 25 but it is to be understood that such changes and modifications may be resorted to as come within the scope of the appended claims.

Referring to the drawing wherein similar reference characters designate like parts in 30 the several views, Figure 1 is an end elevation of an embodiment of the invention, showing it in a closed position, parts being broken away to show the construction; Fig. 2, is an end elevation showing it open, or extended, to serve as a bed; Fig. 3, a view similar to Fig. 1, showing an early stage of the opening movement; Figs. 4 and 5, are fragmentary side elevations depicting stages of the opening movement; Fig. 6, a plan of a 35 modified form of buffer, or shock absorber.

Referring more particularly to the drawing the reference numeral —1— designates a frame of conventional design, which may be varied as desired, —2— a seat-section and —3— a back section. The seat-section is hingedly attached to the forward portion of the frame by suitable means such as hinges —4— secured respectively to end members —5— of the bottom of the frame, and end members —6— of the seat-section. The arrangement being such that in normal, or closed condition the seat-section rests upon the bottom of the frame, the upper surface being suitably upholstered to serve as a seat, 50 and the under surface to serve as a bed section; in its open or unfolded position, the seat-section is reversed, the undersurface being uppermost and in horizontal alinement with the bottom portion of the frame, which is suitably arranged to serve as a bed. To 55 the upper rear edge of the seat-section (as closed) the back-section is hingedly secured by suitable means, such as hinges —7— attached respectively to the end members 6 of the seat-section and the end members —8— of the back-section. In the normal, or closed position the back-section rests against the back of the frame and may project thereabove. The front surface of the back-section is upholstered to match the seat and the rear 60 surface to match the under side of the seat. In opening the bed, the back-section is brought forward and upward, exerting stress on and raising the rear edge of the seat-section (see Fig. 3), with the continued traction, the sections assume the positions shown in Fig. 4. As the seat-section moves forward, it will on passing the vertical position, fall forward and downward carrying with it the rear edge of the attached back-section 65 until the opposing edges of the two sections come together, the two sections are then lowered as one, until a leg —9— contacts with the floor. The back, seat, and bottom of the frame are then in horizontal alinement in 70 position to serve as a bed. The impact of the opposing edges of the seat and back-sections, in the opening movement would be disruptive to the construction were it not that 75 means are interposed to cushion the blow. 75 The cushioning means comprises a spring member interposed between and adapted to yieldingly oppose the closing movement of this joint. As illustrated the cushioning means consists of a sliding member, or bolt 80 —10—, extended through a block —11— secured on the inner side of each of the side members 8 of the back-section and protruding beyond the end of said members in position to be engaged by a block —12— secured 85 on the inner side of the opposing end members of the seat-section. The rear portion —13— of the bolt is reduced in area and has a bearing in a lug —14—. A coiled compression spring —15—, disposed about the reduced part 13 between the lug 14 and a washer —16—, opposes the backward movement of the bolt. In Fig. 6, a modified construction of a buffer is shown, in which a tension spring —17— is attached to brackets —18— and —19— secured respectively on the bolt 90 and the block 11, 95 and the block 11, 100 and the block 11, 105 and the block 11, 110 and the block 11,

Having thus described the invention so that anyone skilled in the art pertaining thereto may make and use the same, we claim:

- 5 1. A davenette comprising a frame, a seat section pivotally connected therewith, a back section pivotally connected with said seat section, said back section movable relative to the seat section in a direction contra to that of the seat section relative to the frame, whereby said section may be opened out into a horizontal plane with the bottom of the frame with one forward movement, means adapted to yieldingly oppose approximation of the edges of the back and seat sections, said means comprising a block attached to an end member of one of said sections, said block having a passage therethrough, a bolt extended through said passage, a projection on the block, a second projection on the bolt, a spring connected with said projections, and a block on the opposing section against which said bolt impinges in the opening movement.
- 10 2. A davenette comprising a frame, a seat section pivotally connected therewith, a back section pivotally connected with said seat section, said back section movable relative to the seat section in a direction contra to that of the seat section relative to the frame, whereby said sections may be opened out into a horizontal plane with the bottom of the frame with one forward movement, said sections comprising end members and connecting side members, means for yieldingly opposing approximation of the edges of the back and seat sections, said means comprising blocks attached to the inner surface of the end members at the opposing edges of said sections, one of said blocks having a passage therethrough, a bolt projecting through said passage, a bracket on said bolt, a second bracket on the associated block, and a spring connected to said brackets and adapted to oppose movement of the block.
